COMBINATION PORTABLE WORKBENCH
AND TOOL KIT

Thomas B. Owens, Cleveland, Ohio

Application May 18, 1945, Serial No. 594,418

3 Claims. (Cl. 144—285)

1

The instant invention relates to combination work benches and tool kits, and particularly to devices of such character that are portable and designed primarily for light work such as the exercise of a hobby, home repair jobs, model building, etc.

The primary objects of the invention are the provision of a combination work bench and tool kit which is quite compact, conveniently carried as a unit, equipped with tools and other accessories required for most wood-working operations, linoleum block-carving, miscellaneous home repairs, etc., and producible at a low manufacturing cost.

The annexed drawing and the following description set forth in detail certain means illustrating the improved combination portable work bench and tool kit, such means disclosing, however, only one of the various forms in which the principle of the invention may be embodied.

In said annexed drawing:

Figure 1 is a top plan of the improved combination portable work bench and tool kit;

Figure 2 is a front elevation;

Figure 3 is an elevation of the left-hand end;

Figure 4 is a fragmentary transverse section taken in the plane indicated by the line 4—4, Figure 2;

Figure 5 is an elevation of the right-hand end;

Figure 6 is a plan, with the top plate or work board proper removed, showing particularly the provisions for storing an assortment of tools in the combination device;

Figure 7 is a perspective, upon an enlarged scale, of a part of the device serving both as a miter box and also as a part of the front wall of the combination device;

Figure 8 is a perspective showing the formation and relative positioning of a certain cast metal part of a vise assembly;

Figure 9 is a fragmentary transverse section, on an enlarged scale, showing particularly the vise assembly; and

Figure 10 is a fragmentary showing of a work-stop and its relative positioning in the device.

Referring to the annexed drawing in which the same parts are indicated by the same respective numbers in the several views, the improved combination device comprises a box-like structure having a base 5, a left-hand wall 6, a right-hand wall 7, a rear wall 8, and a top 11. To complete the box and make of the same a complete housing, members are provided forming a front wall, disposed between the base 5 and the top 11, and these members consist of a miter block 19 extend-

2

ed from adjacently left-hand end wall 6 toward the right to a plane somewhat beyond the center of the box, and a drawer 15 whose front wall extends from a plane closely adjacent the right-hand end of the miter box 19 to a plane adjacent the right-hand wall 7 of the box.

The top 11 is removably secured to the left and right end walls 6 and 7 by screws 11' and, for a purpose hereinafter fully described, extends at the two ends substantially beyond the walls 6 and 7 as indicated by projecting end portions 11² and 11³.

The box-like structure which serves as a combination work bench and tool kit is designed for use upon any suitable and readily available support such as a house table and is provided with rubber feet 25 downwardly extended from the base 5 and serving as a resilient support both to dampen vibration and noise and to obviate marring of the surface of the table or other medium serving as a support for the device.

The front of the top 11 is provided with a hard wood facing strip 13 secured to the top plate proper by screws 13' and projected downwardly somewhat beyond the bottom of the top 11, as clearly indicated in Figure 4, except for a portion thereof, clearly indicated in Figure 2, which is notched so as to allow for a depth of drawer 15 substantially equal to the distance between the top of the base 5 and the bottom of the top 11.

Secured to the base 5 by a screw 36' and spaced somewhat inwardly of the left-hand wall 6 is a block 36 whose front edge is aligned with the front of the base 5 and flush with the hard wood trim surface portion or facing strip 13 of the top 11, this block 36 serving a purpose hereinafter fully described; as also, the space 38 formed between the left-hand wall 6 and the block 36.

A vise block 12 is adjustably mounted upon the front of the device and adjacent the left-hand end thereof, whose rearward face in combination with the adjacent portion of the front facing strip 13 forms an adjustable clamp for holding work. This vise block 12 is mounted upon the threaded stem 21' of a cylindrical plug 21 extended forwardly of the vise block and serving as a mounting for an actuating handle 26. The threaded stem 21' is elongated and passes through the body of the vise block 12 and engages a T-shaped cast metal block 24 whose leg 24' slidably engages the walls of the space 38 and whose head slidably engages open-top aligned slots 28 and 29 formed respectively in the opposing face portions of the left-hand wall 6 and the

block 36. The threaded stem 27' extends at its rear end into the space 38 and there also extends into this space 38 a guide rod 32 which is mounted at its front end in the vise block 12, and passes through the leg and head of the T-shaped metal block 24. The rear face of the vise block 12 is recessed to receive a washer 34 retained by a cotter pin 35, and the guide rod 32 which is forced into the vise block 12 and thus secured therein by a pressed fit is further secured by a pin 33 passed thereto from the front of the vise block 12.

It is evident from the foregoing description that the vise block 12 is readily mounted on and removed from the device, by removing the top 11, and sliding the T-shaped cast metal block up in the slots 28 and 29 and the space 38.

The miter box 19 is formed with suitable miter and square slots 19', as well understood by those skilled in the art, and is also formed with a work support ledge 19² which also serves the additional function, when the miter box 19 is mounted in the device as a part of the front wall thereof, Figure 6, of a stop to prevent the shoving of the miter box beyond its designed position as a part of the front wall of the device, this stop means 19² engaging a drawer guide 22 secured to the top face of the base 5 and a shoulder 23 formed in the block 36 by notching a forward portion of the inside face of said block 36.

The drawer 15 is formed with a knob 16 and the miter box 19 with a knob 20, respective latches 17 and 21 for the drawer 15 and the miter box 19 being pivotally mounted upon the front face of the base 5.

Mounted in the top 11 is a device 14 forming a stop or abutment for work mounted on the top 11, this device 14 simulating a screw and having saw-toothed edges 14' serving to seize and hold the work. The head of the device 14 is mounted in a recess 11⁴ formed in the top surface of the top member 11 Figure 10, and the stem 14² of the device 14 is threaded through a nut 37 countersunk in the bottom of the top member 11 and thence into the left-hand wall 6. It is evident that this structure permits the lifting and lowering of the device 14 by engagement thereof with a screw driver so as to provide a stop and seizure device of the height and character desired for the particular article being operated upon.

It will be evident that substantially the entire chamber formed between the base 5 and the top 11 serves as storage space for a set of tools and such findings as would be most suitable for use in a device of the character described. A part of this space is indicated by 18 between the left-hand wall 6 and the drawer 15 in which several of the larger desirable tools can be stored and transported and the balance of this space is occupied by the drawer 15 which, in part, is a compartment member for holding suitable findings such as screws, nails, nuts, bolts, etc., and, in part, provides a storage space for many smaller tools. Furthermore, the overhanging portions 11² and 11³ of the top 11 provide space both on top and also below on the table support for the disposi-

tion, when working with the device, of tools that are temporarily laid aside or used non-continuously.

What I claim is:

5 1. A combination portable work bench and tool kit comprising a box-like structure having a work board cover and a plurality of spaced interior walls, and a miter-block removably mounted in the structure and forming both an exterior wall 10 of the structure and a closure for an access opening thereinto, the interior walls forming stops positioning the miter-block.

15 2. In a combination portable work bench and tool kit having side and end walls, a base, and a removable work board cover, the sub-combination of a removable vise structure comprising an exterior jaw opposing a kit wall, the latter and the jaw forming a vise clamp, a partition block erected on the base adjacent said wall and also 20 somewhat spaced from another and angular kit wall, the vise structure being slidable upon opposed faces of said block and said angular wall for removal from the kit through the cover opening, and means for actuating the vise clamp.

25 3. In a combination portable work bench and tool kit having side and end walls, a base, and a removable work board cover, the sub-combination of a removable vise structure comprising an exterior jaw opposing a kit wall, the latter and the jaw forming a vise clamp, a partition block 30 erected on the base adjacent said wall and also somewhat spaced from another and angular kit wall, said block and said angular wall having opposed faces within the kit formed with opposed

35 grooves extended toward the cover, the grooves being open-ended adjacent the cover, a block T-shaped in cross section whose arms are slidably mounted in the respective grooves and whose intermediate leg is slidably mounted on, and in the space between, the angular wall and the block, a 40 plug abutting the exterior face of the jaw, and an actuating handle mounted on the plug, the plug having an elongated stem extended through the jaw and having screw-threaded engagement 45 with the T-shaped block.
